The ornamental design for a linear color changer component, as shown and described.

DESCRIPTION

FIG. 1 is a front view of a linear color changer component showing a representation of our new design;
FIG. 2 is a right side view thereof;
FIG. 3 is a rear view thereof;
FIG. 4 is a left side view thereof;
FIG. 5 is a top view thereof;
FIG. 6 is a front perspective view thereof; and,
FIG. 7 is a left side perspective view thereof.
The broken lines in the FIGS. are directed to environment and are for illustrative purposes only. The broken lines form no part of the claimed design.
